UNITED STATES PATENT OFFICE.

JOSEPH E. STRAKER, JR., OF ATTLEBORO, MASSACHUSETTS.

DESIGN FOR A DISH OR CUP HOLDER.

No. 38,697.

Specification for Design.

Patented July 23, 1907.

Application filed June 14, 1907. Serial No. 379,098. Term of patent 7 years.

To all whom it may concern:

Be it known that I, JOSEPH E. STRAKER, Jr., a citizen of the United States, and residing in Attleboro, in the county of Bristol and Commonwealth of Massachusetts, have invented a new, original, and ornamental Design for a Dish or Cup Holder, which is illustrated in elevation in the accompanying drawing, forming part of this specification.

What I claim is:—

The ornamental design for a dish or cup holder as shown.

JOSEPH E. STRAKER, JR.
